UNITED STATES PATENT OFFICE.

WILLIAM A. COOK, OF MARION, INDIANA, ASSIGNOR TO THE MARION MACHINE,
FOUNDRY AND SUPPLY COMPANY, OF MARION, INDIANA, A CORPORATION.

SAND-REEL APPARATUS.

Application filed February 16, 1925. Serial No. 9,621.

The object of this invention is to improve the construction and operation of sand reel apparatus for oil wells and the like. One feature of the invention consists of an improved control of the apparatus from the derrick or a position near the well. The levers for such control are arranged close together in compact form so that the operator can easily reach and operate them, and one hand lever suffices to operate either the clutch or brake for the sand reel or drum or be neutral and the lever for operating the sprocket clutch 10 of the driving mechanism is mounted on the same rod as said clutch and brake lever, and is closely associated therewith.

Another feature of the invention is the particular construction for clutching the driving sprocket in the rig iron mechanism with the band wheel; and another feature is splitting the driving clutch and brake members of the apparatus so they can be readily mounted on or removed from the shafts.

The foregoing and other features of the invention will be understood from the accompanying drawings and the following description and claims.

In the drawings Fig. 1, is a plan view of the apparatus, parts being broken away. Fig. 2, is a view of part of the rig iron mechanism, the upper portion being in elevation, and the lower portion in section and parts being broken away. Fig. 3 is a view of the sand reel mechanism with the frame and the upper portion being in elevation, and parts being in section, and parts broken away. Fig. 4 is a side elevation of the control and other parts of the apparatus, parts being in section, and parts being broken away. Fig. 5 is a section on the line 5—5, of Fig. 4, with parts broken away, and parts shown by dotted lines. Fig. 6 is a plan view and section of the control on the line 6—6, of Fig. 5.

There is shown in the drawings a derrick 10, which is erected over the oil well, and on which is mounted a sheave 11. There is also a walking beam 12, fulcrumed on a beam 112 and extending back and operated by means driven by the shaft 20 of the rig iron mechanism shown on a frame including bars 13, 16 and 17.

The rig iron mechanism has the usual band wheel 21, which is driven by a belt from

an engine not shown. Said wheel has flanges 22. The shaft 20 is mounted in pillow blocks 24, which are on posts, not shown, on the timber 14. A clutch-ring 25, made in semi-circular halves, is secured to the band wheel on its right hand side by bolts 26, and ring 25 has laterally projecting clutch jaws 27 adapted to be engaged by corresponding clutch jaws 28 extending laterally from the sprocket wheel 29, which is loosely and slidably mounted on the shaft 20. It is shown in disengaged or idle position in Fig. 2, but is moved to the left by the collar 30 and yoked bell-crank lever 31 mounted in connection with the post which supports the pillow block 24, and is operated by a rod 32, which extends from the hand operated lever 33, mounted in the control frame 34, located on the floor of the derrick near the well. When moved to the left the sprocket 29 is clutched to the band wheel by the jaws 27 and 28 engaging each other, and then power is transmitted by the sprocket chain 35 to the sand reel mechanism.

In the sand reel mechanism there is a shaft 36 mounted at each end in bearings 37, on stands 38 extending up from the base or the angle iron frame 39. A sprocket wheel 40 is driven by the sprocket chain 35, and it is secured on the hub 41 of a clutch housing 42, that is loose on the shaft 36, and has a circumferential rim internally with which a clutch band 43 frictionally engages. The clutch band is carried by cross arms 44 and is expanded by the toggle levers 45 and 46, that are operated by the lateral movement of the clutch sleeve 47 on the shaft 36. The members 44 of this clutch mechanism are connected with the shaft, so that when the clutch operates, power is transmitted from the sprocket 40 to the shaft 36. This clutch is operated by a loose collar 50, on the sleeve 47, which is actuated by a lever 51 yoke-shaped and fulcrumed between its end to the arm 52 extending from the stand 38. The lever 51 is operated by a connecting rod 53 that is connected with a bell-crank lever 54 mounted on plate 55, as seen in Fig. 4, and which is operated by the rod 56 that extends to the control mechanism at the derrick, as will be further explained.

The brake mechanism consists of the brake wheel 60 secured on the shaft 36, and peripherally engaged by the brake band 61, see Figs. 3 and 4. Said brake band is carried

by the stands 62, on plate 55, and is operated by the toggle construction 63 mounted on said stands 62, and operated by a rod 64 extending to the control mechanism in the 5 derrick.

A cable drum as usual is secured on the shaft 36, and consists of a drum 65, with flanges 66, from which a cable 67 extends to the sheave 11 mounted on the derrick over 10 the well.

The control mechanism, which is illustrated in Figs. 1, 4, 5 and 6, consists of a stationary frame 34, having a top plate 70, that is curved or arcuate as shown.

15 Near one edge this plate 70 has on it a rack 71. Near the bottom the frame 34 carries a rod 72, on which the hand lever 33 is mounted and which operates beside the rack 71. This lever controls the clutch 20 mechanism which shifts the sprocket wheel 29 into and out of driving connection with the band or power wheel. It is held in adjusted position by the spring pawl 73 and released by the bell-crank 74 on the lever 25 33, and the connecting rod 75.

The connecting rod 56, controls the friction clutch on the sand reel mechanism and is connected with a short lever 76, mounted on the rod 72, see Fig. 5, which has a 30 notched upper end adapted to receive the hand lever 77, when moved to the left-hand dotted line position, shown in Fig. 5, and it is operated by said lever 77. The lever 77 is mounted on the rod 72, so as to have lateral oscillation and the arcuate plate 70 has in it a longitudinal slot 78, through which lever 77 extends. In this slot there is a tongue 79 centrally located which extends 40 partially through a slot so as to provide a passage on each side of said tongue for the lever 77, to hold said lever laterally when moved into the passage on either side of the tongue 79. When the lever 77 is in the left-hand side of the slot 78 as shown in Fig. 5 45 it will be held in engagement with the short lever 76 which controls the friction clutch in the sand reel mechanism.

The rod 64 which controls the brake of the sand reel mechanism is pivoted to another short lever 80 in the frame 34 and mounted on the rod 72 and which is similar to but independent of the short lever 76. The short lever 80 is operated by said hand lever 77 when it is thrown over to the right-hand dotted position shown in Fig. 5.

In building the foregoing construction I preferably split or divide into halves the clutch ring 25, the sprocket wheel 29 and collar 30 in the rig iron mechanism so that 60 they may be readily mounted in place on shaft 20 or removed therefrom without disturbing said shaft. Likewise the sprocket 40, clutch housing 42, band wheel 60 and the cable drum 65 are similarly formed in 65 halves so that they can be readily bolted on

the shaft 36 or removed or replaced without disturbing the shaft.

The operation is as follows:

The cable 67 extends from the spool of the sand reel mechanism and passes over the 70 sheave 11 on the top of the derrick of the oil well, and it carries a bailer not shown, used to bail out the oil well. It is to be understood that the band wheel is being driven continuously, whether the sand reel 75 mechanism is in operation or not. When it is desired to operate the sand reel mechanism, the sprocket wheel 29 on shaft 20 is clutched with the band wheel by operating lever 33; and said mechanism remains in 80 operation, without necessarily operating the cable drum on shaft 36 for the sprocket wheel 40 and clutch housing 42 run idly on said shaft. In order to elevate the bailer, friction clutch 43 and 44 is operated by the 85 hand lever 77 being moved into the left-hand dotted line position in Fig. 5. When the bailer descends in the well, said lever 77 is moved to neutral position in slot 78 in the frame 34. The cable drum then will run 90 idly and permit the bailer to descend by gravity. The descent of the bailer, however, is retarded or controlled by the brake drum, and to do this the lever 77 is moved to the right-hand dotted line position shown 95 in Fig. 5. Thus it is seen that one lever 77 is all that is necessary to operate the entire control of the movement of the bailer or cable drum and whether the bailer descends or is being elevated.

I claim as my invention:

1. Control mechanism for a sand reel apparatus and the like, having a rotatable drum, a drive shaft parallel with the drum, means for transmitting power to the drum, clutch and clutch control means for driving said shaft, a clutch on the drum for clutching the power transmission means with the drum, and a friction brake for retarding and stopping the drum, a lever connection for operating the clutch, a lever connection for operating the brake, and a lever connection for operating the power transmission clutch, a frame in which all three of said levers are mounted coaxially, and means for locking the lever for operating the power transmission clutch, substantially as set forth.

2. In sand reel apparatus and the like having a rotatable drum, a drive shaft parallel with the drum, means for transmitting power to the drum, clutch and clutch control means for driving said shaft, a clutch on the drum for clutching the power transmission means with the drum, and a friction brake for retarding and stopping the drum, a lever connection for operating the clutch, a lever connection for operating the brake, and a lever connection for operating the power transmission clutch, a frame hav-

ing a longitudinal slot in the top thereof, a transverse pivot rod in the lower part of the frame on which all three of said levers are pivoted, a locking pawl on the lever for controlling the power transmission clutch adapted to engage indentations in the frame for locking it in adjusted position, a hand lever between the two levers for operating the clutch and brake, and ex-

tending through said slot in the frame and 10 pivoted on said pivot rod so it can be rocked laterally into operative engagement with either of said clutch or brake operating levers, substantially as set forth.

In witness whereof, I have hereunto af- 15 fixed my signature.

WILLIAM A. COOK.
